UNITED STATES PATENT OFFICE.

HURWOOD W. GRIFFITH, OF GEYSERVILLE, CALIFORNIA.

TOILET DEVICE FOR WHEEL-CHAIR INVALIDS.

Application filed August 31, 1927. Serial No. 216,579.

This invention relates to devices to aid in handling wheel-chair invalids—persons who for one reason or another are physically incapacitated and cannot leave their chairs when necessary to use the toilet.

The principal object of my invention is to provide an apparatus by means of which it is arranged to support the weight of an invalid in proper relation to a toilet and which is so designed that the patient is transferred to the apparatus, and vice versa, in a quick and easy manner, with no inconvenience to or movement of the invalid and with but very little physical effort on the part of the attendant or nurse being necessary.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective view of the apparatus.

Fig. 2 is a similar view of a seat element to co-operate with the apparatus.

Fig. 3 is a side view of the device in connection with a patient in a wheel chair, showing the transferring of the invalid from the chair to the device.

Fig. 4 is a fragmentary view showing an enema-vessel support applied to the chest-rest member.

Referring to the numerals of reference on the drawings, 1 denotes a base to be affixed to the floor and having a vertically adjustable member 2 projecting upwardly therefrom and whose movement is controlled by a pedal 3. The form of adjustment and control mechanism I preferably use is the jack type employed in barber shop chairs and the like and being thus of common form, it is deemed unnecessary to illustrate the same specifically.

Turnable in and projecting upwardly from the member 2 is a tubular post 4, supported intermediate its ends for turning and vertical movement by a sleeve-bracket 5 secured to a wall of the bath or toilet room

in which the apparatus is mounted. A hand-actuated clamping member 6 is mounted in the sleeve to engage the post and prevent rotation thereof, when the invalid is being transferred from the wheel chair to the device or when same is in position over a toilet.

At its upper end the post is bent to form a horizontal portion 7 extending away from the bracket 5 a certain distance; said portion being braced against deflection by a diagonal brace 8 connected thereto and to the post below the bracket. Slidably mounted on the portion 7 outwardly of the brace is a sleeve 9 held against movement when desired by a suitable clamping element 10. A short standard 11 is threaded into the sleeve 9 so as to be vertically adjustable with respect thereto. This standard supports a horizontal and transversely extending chest rest pad 12. A foot rest 9a is secured to and projects horizontally from each side of the lower portion of the sleeve 9. Between these foot rests and immediately below the sleeve 9 is swivelly mounted a sleeve 9b in which is adjustably screwed a stem 13 which supports a pair of transversely spaced leg pads 14.

Projecting from the outer end of the member 7 and slidably mounted therein is a stem 15, on the outer end of which is a horizontal fork 16. The prongs of this fork are flat and are spaced approximately six inches apart. In each prong is an upstanding peg 16a which is positioned approximately at the center of the fork to act as stops for the seat member hereafter described. The stem 15 is held against movement and in any desired position by means of a clamping element 17 mounted in the member 7 outwardly of the sleeve 9. Approximately midway between the two prongs of the fork is provided a rod 16b to which the seat member is attached in the manner hereinafter stated as it comes in place on the prongs.

As a necessary feature of the apparatus but separate therefrom I provide a seat in the form of a flat element 18 adapted to rest on the fork 16 and abut against the stops 16a. This seat is to rest transversely of the fork and is longer than the width of the fork, but narrower than the depth of the fork opening. The edge of the seat which is disposed outwardly of the fork is recessed as at 19 for obvious reasons, while

ahead of the recess I provide a yieldable bracket 20 to detachably support a urinal of any suitable type. At the center of the inner edge of the seat member is hinged a notched ratchet element 18^a adapted to move into locking engagement with the rod 16^b as the seat is advanced onto the fork so as to prevent undesired movement of the seat relative to the fork while the apparatus is in use. The edge of the member 12 farthest from the fork is provided with socket elements 21 to detachably support a vertical rod 22 or the like. This rod carries one or more hooks 23 to support an enema holding vessel. 15 The apparatus is mounted in the room in such relation to the toilet that when the post is swung in one direction, the fork will overhang the toilet.

In operation the post 4 is first adjusted so that the fork 16 will be disposed in a horizontal plane immediately above that of the seat cushion 24 of the wheel chair 25 occupied by the invalid. The seat 18 is then placed on the cushion under the invalid in a position about the middle of his thighs so as to support the body weight, and the urinal put in place if needed. The chair is then wheeled up to the apparatus, with the fork directly facing the chair. The attendant then elevates the seat member 18 slightly with one hand and with the other moves the chair still further forward until the fork passes under the seat 18 centrally of the length thereof. Then the invalid is bent forward until his chest engages the pad 12 (which is first adjusted lengthwise of the member 7 to suit) and this elevates the invalid so that the wheel chair is now free to be wheeled back out of the way. The locking device 6 is then released and the post 4 is then swung gently to one side until the invalid is properly superimposed over the toilet. To replace the invalid in the chair the reverse operations are carried out.

45 The apparatus may of course be also used in placing the invalid under a shower. The above described operations are carried out when the patient is completely incapacitated physically, and in this case the leg rest 14 is not used and may be removed if desired so as not to be in the way, or the swivel mounting of the leg rest will allow this member to swing back against the brace 8.

55 The leg rest is particularly intended for use in connection with a patient having an injured leg, which must of course be supported when the patient is transferred from the chair to the apparatus. The foot rest attached to the lower part of the sleeve 9 is to be used when an enema is being given, since because of their position they hold the legs in a flexed attitude. In this case the chair is not withdrawn entirely clear of the patient, and he leans back against the seat of the chair while the legs are supported

by the foot rest. The chest pad is not then of course engaged with the patient and the rod 22 is mounted thereon to support the bag or other receptacle for the enema. Also in this case it is evident that a receptacle, such as a bed-pan, may be used. 70

The various features of the apparatus enables the same to be accommodated to any height of wheel chair or toilet and to any size of patient. 75

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims. 80

Having thus described my invention what I claim as new and useful and desire to secure by Letters Patent is:

1. An apparatus for the purpose described including a post, means for supporting the post in a fixed vertical position, a horizontal member supported from the post and adapted to project over the seat of a wheel chair, and a seat element to support the weight of a patient in the chair adapted to detachably rest on the member to be supported thereby. 90

2. An apparatus for the purpose described comprising a turnable post, means for supporting the post in a fixed vertical position, 100 a horizontal extension on the upper end of the post, a chest-rest pad slidably mounted on the extension, and an element to support the weight of a patient slidably mounted in and projecting from the outer end of the extension. 105

3. An apparatus for the purpose described including a vertical post, a horizontal member projecting laterally from and supported by the post, said member being adapted to project under the thighs of a wheel-chair patient to support the weight of such patient, and a chest-rest pad above the member and supported from the post, said pad being disposed between the member and post. 110

4. An apparatus for the purpose described including a vertical post, a horizontal member projecting laterally from and supported by the post, said member being adapted to project under the thighs of a wheel-chair patient to support the weight of such patient, and means for adjusting the member horizontally relative to the post. 120

5. An apparatus for the purpose described including a vertical post, a horizontal member projecting laterally from and supported by the post, said member being adapted to project under the thighs of a wheel-chair patient to support the weight of such patient, a chest-rest pad above the member and means 125 130

supporting the pad from the post for horizontal adjustment between the post and member.

6. An apparatus for the purpose described including a vertical post, a horizontal member projecting laterally from and supported by the post, said member being adapted to project under the thighs of a wheel-chair

patient to support the weight of such patient, and leg-rest pads under the member 10 and supported by the post, said pads being located between said member and the post.

In testimony whereof I affix my signature.

HURWOOD W. GRIFFITH.
